CLAIM

The ornamental design of a combined faucet body and spout, as shown and described.

DESCRIPTION

FIG. 1 is a front perspective view of a combined faucet body and spout showing our new design;
 FIG. 2 is a rear perspective view thereof;
 FIG. 3 is a top plan view thereof;
 FIG. 4 is a front elevational view thereof;
 FIG. 5 is a left side elevational view thereof;
 FIG. 6 is right side elevational view thereof;
 FIG. 7 is a rear elevational view thereof; and,
 FIG. 8 is a cross-sectional view of the spout taken along line 8—8 in FIG. 1.

The broken line showings of the base handle and aerator in FIG. 1 for purposes of illustration only and form no part of the claimed design.
